UNITED STATES PATENT OFFICE

2,419,091

COMPRESSOR AND COMPRESSOR VALVE

Arthur Freeman Sanders, Leeds, England

Application September 8, 1943, Serial No. 501,582
In Great Britain September 26, 1942

6 Claims. (Cl. 230—222)

1

The ordinary reciprocating compressor has an outlet or transfer valve which should be opened for a considerably less period than the exhaust valve of an internal-combustion engine, and which should preferably be opened at a moment when the pressure in the compressor is such that there will be little or no resurgence of gas from the receiver to which the compressor delivers.

My main object is to provide an improved form of transfer valve for use in a reciprocating compressor, but the invention is not limited in this respect.

For a better understanding of this and other objects and advantages of the invention attention should be directed to the following description in which reference is made to the accompanying drawing the single figure of which is a sectional elevation of a transfer valve and actuating means, according to the invention, for a reciprocating compressor.

The invention broadly consists in a reciprocating compressor having an outwardly-opening poppet valve which is positively moved in the closing direction in timed relation to the compressor, the receiver pressure serving for holding it closed thereafter. The closing may be effected by cam or other actuating means acting on the valve stem through a hydraulic device. If the plunger of the latter is of greater cross-section than the cross-section of the valve stem, the stroke of the valve will be proportionately greater than the effective stroke of the plunger—i. e., the valve can be closed in less time for a given actuating means than if the latter acted directly upon the valve stem. The plunger and valve stem need not be aligned with one another. The actuating means may include a cam acting directly upon the plunger or indirectly thereon through a rocker, the plunger being spring-returned in either case, or, alternatively, in order to avoid the necessity for the use of springs in the case where high speeds may be involved, it may take the form of an eccentric strap of which actuates the plunger positively in both directions.

In the construction shown in the drawing, the reciprocating piston 11 of the compressor works within a cylinder 12. 13 is a normal form of inlet valve and 14 an outwardly-opening poppet valve for transferring the compressed air from the cylinder to the receiver passage 15. The valve stem 16 operates in the smaller bore of a valve guide having a larger bore in which a plunger 17 operates, and between the two is hydraulic liquid 18. The plunger is shown as pressed

2

outwardly by a spring 19, its head coacting with a cam 20 on a shaft 21.

Preferably, I provide a bleed hole 23, for the hydraulic fluid, which can act as a safety valve should the valve 14 be seated before the end of the plunger stroke or before the operating pressure is released. If desired, the arrangement may be such that the bleed hole is only uncovered by the valve stem when the valve is almost operated, e. g., closed.

One object of the invention is to provide means for the abnormally rapid closing of the transfer valve. Due to the high speed of closure and the additional closure force of the excess of pressure in the receiver over that in the compressor as the compressor piston is returning on the suction stroke, i. e., at the beginning of that stroke, there is a tendency for the valve to strike the valve seating 25 with high velocity. It is therefore very desirable to make the valve seating of some stiff resilient material of high internal friction. It is conveniently in the form of a simple cushion valve seat bonded to an oil- and heat-resisting synthetic rubber.

25 In operation, the arrangement is such that the pressure in the receiver to which the compressor delivers (i. e., in the receiver passage 15) will assist in the final closing of the valve 14 and in maintaining the valve closed. The cam means 30 preferably gradually releases the operational (i. e., closing) pressure on the plunger, as will be seen from the shape of the cam at 27. A bleed hole—for example, that marked 28—will allow the return flow of fluid as the plunger is being withdrawn.

The plunger is shown as coacting in a known way with ports 29 through which a reservoir 30 for the hydraulic fluid communicates with the space below the plunger when the latter is at out 40 centre, the bleed hole 23 communicating with this reservoir. The pressure therein may be maintained by a pump (not shown), excess fluid being returned to the inlet side of the pump, also in a known manner. The ports are arranged in such 45 manner that the inward motion of the plunger sets up no appreciable pressure in its cylinder bore until it is closing the ports. Thereafter the valve stem is subject to pressure which brings the valve 14 on to its seating or preferably very close thereto. The timing of the closing of the valve is sensibly fixed by the plunger reaching its in-centre, as shown, or, alternatively, by uncovering a relief port in its cylinder barrel, whereby the operational pressure on the valve stem is ended—this latter arrangement not being illus-

trated but being well known in connection with fuel pumps for injection engines.

Preferably, the operational pressure on the plunger will be completely withdrawn well before the compressor pressure will in ordinary conditions have reached the receiver pressure, so that the transfer valve can open as pressure conditions in compressor and receiver permit, and so open earlier than will be demanded in ordinary conditions when this should be necessary—for example, when first starting up. The valve may open towards the end of the withdrawal stroke of the plunger, while the latter is fully withdrawn, or during the beginning of the operational stroke of the plunger, and the free end of the latter remote from the cam means is preferably provided with a recess 32 to receive the end of the valve stem with slight clearance, so that if the plunger should be engaged upon its operational stroke a friction buffer effect would be provided (when the plunger might otherwise make direct contact with the stem) when the valve is first being accelerated in the closing direction.

In the case of a reciprocating compressor for supercharging a compression-ignition engine operating with fuel injection, I may use fuel oil as the hydraulic fluid, as any leakage of fuel oil would be carried through into the receiver and subsequently used in the engine.

What I claim as my invention and desire to secure by Letters Patent of the United States is:

1. In a reciprocating compressor, a receiver passage for compressed fluid, an outwardly opening poppet valve for passing compressed fluid from said compressor to said receiver passage, said valve having the external surface of its head exposed to the pressure in said receiver passage, means for positively moving said valve in the closing direction in timed relation to said compressor, and a hydraulic travel increasing device interposed between said valve closing means and the valve stem for enhancing the closing speed of said valve.

2. An arrangement according to claim 1 in which said hydraulic device comprises a hydraulic cylinder, a piston constituted by the valve stem received in a bore of said cylinder, a plunger of greater cross-sectional area than said valve stem received in a corresponding bore in said cylinder and acted upon by said valve closing means to close said valve at a greater speed than that imparted to said plunger, and means for restor-

ing said plunger to the position corresponding with the open position of said valve.

3. In a reciprocating compressor, a receiver passage for compressed fluid, an outwardly opening poppet valve for passing compressed fluid from said compressor to said receiver passage, said valve having the external surface of its head exposed to the pressure in the receiver passage, a hydraulic cylinder, a piston constituted by the valve stem received in a bore of said cylinder; a plunger of greater cross-sectional area than that of said valve stem received in a corresponding bore in said cylinder, means for positively moving said plunger in the direction for it to close said valve at a speed greater than that imparted to said plunger and in timed relation to the compressor, means for restoring said plunger to the position corresponding with the open position of said valve, a hydraulic reservoir, and means for providing a communication between said hydraulic cylinder and reservoir to permit said plunger to respond to the restoring means while said valve is closed.

4. An arrangement according to claim 3 in which the hydraulic cylinder is ported in a position that permits the escape of hydraulic fluid to the hydraulic reservoir until said plunger nears the inner end of its stroke and closes said port.

5. An arrangement according to claim 3 comprising a recess in the end of said plunger adapted to receive the adjacent end of the valve stem with clearance and thereby, in conjunction with the hydraulic fluid, to provide a cushion buffer.

6. An arrangement according to claim 3 comprising a resilient damper seating for the valve.
